UNITED STATES PATENT OFFICE.

FRANK A. LUNDQUIST, OF CHICAGO, ILLINOIS, ASSIGNOR, BY MESNE ASSIGNMENTS,
TO WESTERN ELECTRIC COMPANY, INCORPORATED, A CORPORATION OF NEW
YORK.

AUTOMATIC TELEPHONE-EXCHANGE.

1,369,288.

Specification of Letters Patent. Patented Feb. 22, 1921.

Application filed August 21, 1900. Serial No. 27,549.

To all whom it may concern:

Be it known that I, FRANK A. LUNDQUIST, a citizen of the United States of America, and a resident of Chicago, county of Cook, and State of Illinois, have invented certain new and useful Improvements in Automatic Telephone-Exchanges, of which the following is a specification.

My invention relates to automatic telephone exchanges. The principal feature of this invention resides in the provision of means whereby when two switches make connection to the same line, the talking conductors to the brushes of the switch last to 10 make connection to the line will be interrupted.

In the present application the central office apparatus of a telephone exchange is arranged with its devices in two groups respectively called main switches and auxiliary switches. The main switches and auxiliary switches are substantially the same in construction and operation,—the 20 differences between the two being principally in the electrical connections made by them rather than in the operation and construction.

In the accompanying drawings Figure 1 is a front elevation of a main switch and corresponds to Fig. 4, which is a front elevation of the same switch used as an auxiliary switch; Fig. 2 is a rear elevation of an auxiliary switch; Fig. 3 is a side elevation of an auxiliary switch; Fig. 5 is a detail in plan showing part of the switch as it would be on either the main or auxiliary switches; Fig. 6 is a detail in side elevation, partly in section, showing some of the operating parts as arranged on an auxiliary switch; Fig. 7 is a plan of the switch carriage detached; Fig. 8 is a section on line 8—8 of Fig. 7; Figs. 9 and 10 are details; Fig. 11 is a general diagram showing the electrical connections between two main switches and one auxiliary switch, with a detached portion of a second auxiliary switch to show the manner in which the non-interfering device is operated and Figs. 12, 13 and 14 taken to

gether form an abridged diagram showing the arrangements for interconnecting the 50 non-interfering devices in exchanges of the kind illustrated in my Patent No. 776,524, issued Dec. 6, 1904.

Briefly stated, a switch consists of some contact points and contact makers therefor, 55 a magnet A, for moving the contact makers in one direction, a second magnet B, for moving them in a direction perpendicular to the first movement, and certain other magnets, C. D. and E, for making and breaking 60 electrical connections as will be hereinafter described. In the said drawings F. is a vertical frame on which is secured a piece of insulation F¹ in which insulation are a series of contact points F². Secured on the face 65 of the frame F are three posts F³ which serve as guides for a carriage G, which carriage is made up of two parallel bars G and a third bar parallel to the other two, but located below and between them. These side 70 bars are connected together by cross-bars G² and on the bar G² is mounted a second carriage H. On the carriage H is a piece of insulation H¹ (Fig. 7) which, in the main switch, carries two contact makers P and P¹, 75 and in the auxiliary switch carries three contact makers, which for convenience have been marked P², P³ and P⁴. On the bar G¹ of the first carriage is a ratchet rack G³ having teeth facing in two directions, and the 80 carriage H is a similar ratchet rack with teeth facing in two directions. On the back of the frame F is secured a magnet A on the armature lever A¹ of which is a pawl A² adapted to engage the ratchet G³ so as to 85 move the carriage upward in its guides F³. Supported on a post A⁴ is a pawl A⁵ which engages the ratchet G³ so as to hold it in the position into which it has been moved by the operation of magnet A. Also on the back of 90 the frame F is a magnet B whose armature lever B¹ carries a pawl B² adapted to engage the ratchet teeth of the carriage H and move said carriage transversely to the movement of the first mentioned carriage. Secured to 95 a bracket G⁶ on the carriage G is a holding

pawl H^2 adapted to prevent a return movement of the carriage H until it has been released. On the rear end of the pawl H^2 is a tail piece H^3 arranged to engage the pin J^2 and release the pawl H^2 from engagement with the ratchet on the carriage H when said carriage is at its lowest position.

It will be observed from this description that the magnet A moves the carriage upward the required distance and that the magnet B moves the second carriage transversely any required distance. The result of the action of these two magnets is to move the contact makers P and P^1 of the main switch, or P^2 , P^3 , and P^4 of the auxiliary switch, over the rectangularly arranged contact points F^2 .

Supported on the frame F is a post J to which is pivoted a lever J^1 normally held by a spring in contact with the post J^2 . Pivoted to the lever J^1 is another lever J^3 which projects toward the middle of the machine and over the armature lever A^1 , as is shown in Fig. 9. Between the ends of the lever J^3 is a hook which lies adjacent to a tail piece A^6 on the holding pawl A^5 . If the lever J^1 be moved to the left from the position as shown in Fig. 9, the hook on the lever J^3 will engage the tail piece A^6 on the pawl A^5 , when, if the lever J^1 be then permitted to move to the right against the stop pin J^2 , the said hook will draw the pawl A^5 out of engagement with the ratchet G^3 , thereby releasing it and permitting the carriage to drop to its lowest position, which lowest position is determined by the post F^4 and a set-screw F^5 , against which the bar G^4 strikes. On the carriage H is a spring H^4 , one end of which is attached to a pin H^5 in the carriage H , and the other end of which is attached to a pin H^6 secured to the right hand side bar G of the main carriage. The spring H^4 is arranged to draw the carriage H to the right to its extreme or normal position when released from its holding pawl H^2 . The position of the spring H^4 is such that its action is directly in line with the travel of the carriage H , so that in drawing it back to its normal position there is practically no lateral strain to produce frictional resistance. In the same way the main carriage, by moving directly upward and being guided in easily fitting guides in posts F^3 , is, when released, entirely free from lateral strain. By arranging these two carriages so that when they are released they are free to move independently of any outside strains, I am enabled to make the propelling mechanism lighter than would otherwise be the case. On the lower right hand part of the switch, as shown in Figs. 1 and 4, there is a magnet D whose armature lever D^1 is arranged to make certain electrical connections. In the main switch this magnet makes only one such electrical connection,

while in the auxiliary switch it makes two electrical connections and breaks a third. On the armature lever D^1 of the switch used as a main switch, there is a second lever D^3 which extends upward into engagement with a pin J^5 secured to a lever J^4 , which last lever is also pivoted to the lever J^1 . The outer end of the lever J^4 is provided with a hook which is adapted to engage a pin B^5 which projects from the side of the armature lever B^1 . In its normal position the lever J^4 is not in the path of the pin B^5 when the magnet B operates to move the carriage H to the left. If, however, the magnet D should be energized at the same time the magnet B is energized, then the projecting arm D^3 will push the pin J^5 so as to raise the lever J^4 into the path of the pin B^5 , so that the action of the magnet B will be to push the lever J^4 to the left and cause the hook thereon to release the pawl A^5 as has been previously described. The same result would occur if the armature lever A^1 be moved upward immediately before the magnet B operates and is then released before the magnet B is demagnetized. This will be observed from Fig. 9 as it will be seen that the movement upward of the armature A^1 pushes the levers J^3 and J^4 into the path of the pin B^5 , when upon the release of the lever A^1 the lever J^3 will drop into engagement with the tail piece A^6 on the pawl A^5 . It will, therefore, be apparent that the action of the magnet A and magnet B together, or the action of magnet D and magnet B together, will result in releasing the pawl A^5 and permitting the carriage to drop to its lowest position. The instant the carriage reaches its lowest point the tail piece H^3 on the pawl H^2 strikes the pin J^2 and releases the carriage H , which is then retracted by the spring H^4 . At the left front side of the main switch is a magnet C which is arranged to move a contact maker 23 from the contact 24 to a contact 53. Supported adjacent to the magnet C is a pivoted lever C^2 which is engaged by the pin G^5 on the bar G^4 when the main carriage is at its lowest position. The armature lever C^1 , which carries the contact maker 23, projects adjacent to the lever C^2 but is not engaged by said lever when the lever is engaged by the pin G^5 . If, however, the pin G^5 be moved upward so as to leave the lever C^2 free, then if the magnet C be energized, the armature lever C^1 will be caught by hook on the end of the lever C^2 thereby holding the contact maker 23 away from the contact 24 and into engagement with the contact 53. On the back of the auxiliary switch as shown in Figs. 3 and 6, there is supported a magnet E provided with an armature lever E^1 . The end of the armature lever E^1 is provided with a hook E^2 which lies adjacent to a hook A^3 on the armature lever 130

A¹ of the magnet A. These parts are so arranged that if the magnets A and E operate simultaneously, then the hook E² will be caught by the hook A³ and be held with the 5 armature lever E¹ out of engagement with two contact points 43 and 79 as shown in the upper part of the diagram Fig. 11. The operation of the parts E² and A³ will be more readily understood by the inspection 10 of said diagram than by the parts themselves as shown in Fig. 2.

The difference between the contacts made by the magnets on the main switches and those made by the magnets on the auxiliary 15 switches may also be best seen by inspection of Fig. 11. Thus, the armature lever A¹ of a main switch, when moved by its magnet A, opens the electrical connection at a spring 30, and closes connections between 20 contacts 36 and 37, 50 and 51, and 95 and 96. The same movement on an auxiliary switch operates in a similar way similar contacts, for example, it opens connection to contact point 45, closes connection between 25 contacts 81 and 82, and shifts the contact spring 89 from connection with contact point 91 to connection with contact point 88. In the main switch the magnet D closes one contact while in the auxiliary 30 switch it closes two contacts and opens a third.

In arranging a telephone exchange I place the central office devices in the manner which is illustrated in my Patent No. 35 776,524, issued December 6, 1904, to which reference may be had for an illustration of the general principles of grouping main and auxiliary switches. Briefly described that manner is as follows:—

40 I place a large number of main switches in a row, or in any convenient manner, and these I divide into comparatively large groups depending upon the number of contact points arranged in the auxiliary 45 switches. In this case there would be sixty such main switches in a group; and for each group of main switches I provide a smaller group of ten auxiliary switches. The first vertical row of contact points on a main 50 switch represents, or are connected to, the different auxiliary switches of the first group; the second row of contact points are similarly connected to the second group, and so on. In the auxiliary switches the contact 55 points that are set off for the pointers P² and P³ are connected to the normal contact points of different main switches.

The general arrangement is illustrated in the condensed diagram of Figs. 12, 13 and 60 14, which diagram shows one group complete and a part of a second group.

In operating the exchange a subscriber first closes the contact point marked 1st at his telephone, as is illustrated in Fig. 11, the 65 result of which is to move the carriage of

the connected main switch up one step. He then closes the second contact point a required number of times, which results in moving the carriage H and, consequently the pointers P and P¹, laterally to a required vertical row of contact points. He then closes the first contact ten successive times to move the carriage upward. The connections are so arranged that when the pointers P and P¹ reach a connection to an auxiliary switch which is not employed, the connection to the moving magnet is broken and the unemployed auxiliary switch is automatically moved from its position so that it can not be reached by any other main switch and is, consequently, transferred from the unemployed to the employed class. He then closes the second contact which moves the auxiliary switch upward one step. He then closes the first contact point 75 the required number of times which results in moving the carriage H of his auxiliary switch laterally to the required vertical row of contact point. He then closes the second contact a required number of times, which 80 moves the pointers P² and P³ upward to the required or selected contact points which are connected with the required switch of the telephone which is to be called.

Taking these operations in detail, when 95 the calling subscriber closes the first contact point once, a current flows as follows: Battery X—100—20—telephone station—21—22—23—24—25—26—A—27—99—X. This moves the carriage of his switch upward one step and brings the ratchet on the carriage H in line with the pawl B² which is operated by the magnet B, so that an operation of the said magnet will move the carriage H laterally. The pawl B² is so 100 located that when the carriage has been moved upward one step the said pawl is in line with the ratchet on the carriage H, but when moved up two steps they are out of line with each other, and consequently, an 105 operation of the magnet B will not affect the carriage H. Therefore, he closes the first contact only once. Closing the second contact sends a current as follows: X—100—20—110 telephone station—28—29—30—A¹—carriage—31—32—33—B—27—99—X. This moves the carriage laterally and is repeated the required number of times to bring the pointers P and P¹ to the required vertical 115 rows. Closing the first contact ten times results in moving the carriage upward until the pointers P and P¹ reach contact points which are connected to an auxiliary switch 120 which is not in use when, by reason of contact made between 36 and 37 at each operation of the magnet A, a current flows as follows: Y—34—35—36—37—38—C—39—40—P¹—41—42—E¹—43—44—45—A¹ of the auxiliary switch carriage—46—47—D—48—49—Y. The current through C of the 130

main switch breaks the circuit for the magnet A at 23-24, thereby automatically stopping the carriage of the main switch in connection with the first auxiliary switch found unemployed. It therefore follows that all of the ten contacts made, more than enough to connect to the idle auxiliary switch, are not effective. The reason for making ten contacts is that, as previously stated, the ten contact points in a vertical row are connected to the ten auxiliary switches constituting one group, and, as an undetermined number of these are normally in use, it is necessary to move the main switch far enough to reach one that is unemployed. If it so happens that none is employed when the main switch is moved, then the moved main switch will automatically stop at the first contact point. The same result would happen if the first auxiliary switch was unemployed while several of the others were in use. If, however, the first is employed by some other main switch, then the moved main switch will pass over the contact point connected to the first auxiliary switch and be automatically stopped at the first one unemployed. As it may frequently happen that the first nine auxiliary switches are employed while the tenth is not, it is therefore desirable to always make ten contacts so as to be sure to reach an unemployed switch. Besides, as the calling subscriber is not at the central office and has no means of knowing what auxiliary switches are employed and what unemployed, his only practical method of being sure to reach one of the ten is to make contacts enough to reach the last of the series in case all of the others are in use. To prevent the break at 23-24 from releasing magnet A before the second operations are completed, there is a shunt from 21 to 25 by way of 50-51-52, which is closed by the magnet A and which holds the current through itself until the circuit is broken at the telephone. Breaking connection at 23-24 closes it between 23 and 53, and as this occurs after the carriage has been moved up, the catch C² is free to catch the armature lever C¹ and hold the connection between 23 and 53 to be used in the next contact made at the telephone. The current through D of the auxiliary switch closes 55 and 56 when a current flows as follows: X-100-54-55-56-57-58-A of the auxiliary switch-59-60-99-X. The current through A of the auxiliary switch moves its carriage up one step breaking the connection between the carriage and the contact 46, thus preventing some other switch from connecting its magnet C in series with the magnet D of this auxiliary switch. This action, therefore, removes the auxiliary switch from the class of the unemployed to the class of the employed switches. To

prevent the break between the carriage and 46 from releasing magnet D too soon, there is a shunt from 41 to 47 by way of 61-62-63, which is closed by the magnet D, and which holds the current through itself until the line is broken at 36-37 by the releasing of the magnet A of the main switch. Then closing the second contact a current flows: X-100-20-telephone station-28-29-30-A¹-carriage-61-D-62-P-selected contact point-58-A of the auxiliary switch-59-60-99-X. This moves the auxiliary carriage upward to connection with the contact 93. Then closing the first contact a current flows: X-100-20-telephone station-21-22-23-53-39-40-P¹-41-42-E¹-43-44-45-A¹ of the auxiliary switch-carriage-93-64-65-B-66-67-68-60-99-X. This moves the carriage H of the auxiliary switch laterally to the required row. Then closing the second contact results in moving the carriage upward as previously described and is repeated to reach the required contact point.

In this condition the talking circuit is as follows: calling telephone 28-29-30-A¹-carriage-61-D-62-P-58-78-79-69-P²-selected contact point on the auxiliary switch-70-71-72-normal contact point of the called switch-P¹-40-95-73-74-25-24-23-22-21-called telephone-28-29-30-A¹-carriage-61-D-62-P-75-76-77-P³-carriage-A¹-45-44-43-E¹-42-41-P¹-40-39-53-23-22-21-calling telephone station. To release, both the first and the second contacts I close simultaneously, when a current flows X-100-telephone station-28-29-30-A¹-carriage-61-D-62-P-58-A of the auxiliary switch-59-60-99-X. D closes D¹ to 80 and A of auxiliary switch closes 81 to 82. When a current flows X-100-20-telephone station-21-80-D¹-B-27-99-X. Also X-100-20-telephone station-21-22-23-53-39-40-P¹-41-81-82-65-B of the auxiliary switch-66-67-68-60-99-X. This operates D and B of the main switch, and A and B of the auxiliary switch, which as previously described, releases the holding pawls of both switches and permits the carriages to drop back to their normal positions.

For convenience in arranging the switches and connecting them together there are banks of wires like 71 and 76, at the upper part of Fig. 11, which connect the contact points belonging to the pointers P² and P³, and from these wires branches, as 72 and 75, extend to the normal contact points of the different main switches. This arrangement of banks of wires and their branch connections is similar to that shown in my previously mentioned Patent No. 776,524, and, also, similar in a general sense to well

known connections. In addition to these wires just described there is an additional set or bank of wires for each group of auxiliary switches represented by 84. These wires inter-connect the contact points on the auxiliary switches which are appropriated to the pointer P^4 , for example: The wire 84 would have branches 83 to a corresponding contact point on each and every auxiliary switch in the exchange when there is only one group of auxiliary switches as shown in Fig. 11. When there are a plurality of groups, as shown in my before mentioned patent, then there is a separate set or bank of these wires 84 for each group of auxiliary switches. Other wires belonging to this bank would have corresponding branches to their contact points on the auxiliary switches. At the right hand upper portion of Fig. 11 there is a detached portion of a second auxiliary switch which corresponds to the portions similarly marked in the auxiliary switch which is provided with a complete diagram. There is provided a battery Z which is connected to all of the magnets E of the auxiliary switches in the manner which is shown. If while the auxiliary switch which we have been previously describing as having made the connection between two main switches is on the points connected to the bank wires 71—76 and 84, a second auxiliary switch moves its pointer P^4 to a contact point corresponding to the same bank wire 84, then a current from the battery Z will flow as follows: Z —85—86— E of the auxiliary switch which has last moved to this connection—87—88—89—(magnet A of the second auxiliary switch being in the act of moving to the designated point)—90— P^4 —83—84—83 of the auxiliary switch which first moved to the operating connection, P^4 —90—89—91—92— Z . This energizes magnet E of the auxiliary switch last moved to the connection and as this occurs while A^1 is attracted then upon the release of both magnets A and E — E^1 will be caught by the hook on A^1 , and E^1 will be held from 79 as shown at the right upper hand part of the diagram. As the talking circuit passes through 79 of the selected auxiliary switch, it will be evident that the talking circuit is broken when the auxiliary switch moves to a connection which is previously occupied. The magnet E and its connections, therefore, constitute a non-interfering device which does not prevent the auxiliary switch from being moved to any position, but does prevent a moving auxiliary switch from interfering with any talking circuit that has previously been made.

In tracing this non-interfering circuit through the condensed diagram any one of the auxiliary switches in the upper part of Figs. 12 and 13 may be assumed to be the

first in connection with a called station, and either of the others the second or interfering switch.

The auxiliary switch of Fig. 14, being interconnected in a separate group of auxiliary switches, does not operate through any of the connections made by those of Figs. 12 and 13.

What I claim is:

1. In a telephone system, an exchange, subscribers' lines terminating thereat, pairs of talking conductors at said exchange, switches for respectively connecting said pairs of conductors to any desired line, a circuit breaking device at each switch, and an electromagnet operated upon two switches making connection to the same line to cause said circuit breaking device to interrupt the conductors of the last connected pair. 75

2. In a telephone exchange system, telephone lines, pairs of talking conductors, switches having brushes for extending said pairs of conductors respectively, multiple terminals of said lines arranged to be traversed by the brushes of said switches, a circuit controlling device at each switch, and means for operating said controlling device when a second switch engages the contacts of a line to interrupt the pair of conductors terminating in said switch. 80

3. In a telephone system, subscribers' lines, connector switches, multiple terminals of said lines at said switches, selector switches, talking conductors terminating at said connector switches respectively, multiple terminals of said conductors at said selectors, means for automatically operating a selector switch to pick a conductor terminating at an idle connector switch, a circuit controlling device at each switch, and an electromagnet operated when a second switch unites with one of said lines to cause the circuit controlling device of the second switch to interrupt the conductors leading from a selector to said switch. 95

4. In a telephone system, a pair of metallic circuit subscribers' lines leading to a central office, selecting switches at said central office, trunk lines controlled by said selecting switches for connecting said pair of lines together, a pair of controlling magnets at each of said selecting switches simultaneously bridged across the talking circuit between said two stations, a source of current adapted to supply current to the limbs 115 of said line through said magnets, and means at one of the subscriber's stations for closing the circuit through said magnets for the operation of said switches, substantially as described. 120

5. In a telephone system, a metallic talking circuit extending in two limbs from a central station to a substation, a plurality of selecting switches at the central station for extending the limbs of said talking cir- 125

cuit, a source of current at the central station, a controlling magnet for each of said selecting switches simultaneously connected between one limb of said talking circuit and 5 a terminal of said source, another controlling magnet for each of said selecting switches connected between the other limb of said talking circuit and the same terminal of

said source, and a return path for the other terminal of said source.

Signed at Chicago, Ill., this 25th day of July 1900.

FRANK A. LUNDQUIST.
